UNITED STATES PATENT OFFICE.

WILLIAM LANGE, OF BENTLEY, NORTH DAKOTA.

COMBINED DOOR LATCH AND HOLDER.

1,118,560.

Specification of Letters Patent.

Patented Nov. 24, 1914.

Application filed December 10, 1913. Serial No. 805,829.

To all whom it may concern:

Be it known that I, WILLIAM LANGE, a citizen of the United States, residing at Bentley, in the county of Hettinger, State of North Dakota, have invented certain new and useful Improvements in Combined Door Latches and Holders; and I do hereby declare the following to be a full, clear, and exact description of the invention, such as will enable others skilled in the art to which it appertains to make and use the same.

This invention relates to a combined door latch and holder.

The principal object of the invention is to provide a door latch of novel construction including a spindle and a holder adapted to be secured to the wall for engagement with the spindle to retain the door in its open position.

Another object of the invention is to provide a device of the character described in which the holder may be readily disengaged from the spindle upon rotation of the latter.

A further object of the invention is to provide a device for the purpose set forth which is composed of a minimum number of parts, is therefore simple in construction, and is cheap to manufacture.

With these and other objects in view, the invention consists in the construction and novel combination of parts hereinafter fully described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

In the drawings: Figure 1 is a front elevation of a door showing the application of my invention, Fig. 2 is an enlarged top plan view thereof showing the door retained in its open position by the holder, Fig. 3 is an enlarged detail side elevation, showing the latch in its elevated position, Fig. 4 is a similar view but showing the latch in its lowered position, Fig. 5 is a view partly in section and partly in elevation of the door latch, Fig. 6 is a cross sectional view taken

on the line 6—6 of Fig. 5, Fig. 7 is a perspective view of the door latch casing, Fig. 8 is a perspective view of the gravity wall latch, Fig. 9 is a cross sectional view through the holder taken on the line 9—9 of Fig. 1, and Fig. 10 is a longitudinal sectional view through the holder, Fig. 11 is a detailed elevation showing the spring arrangement, Fig. 12 is a detail perspective view.

Like reference numerals designate corresponding parts in all the figures of the drawings.

Referring to the drawings, 5 designates a swinging door of any suitable construction, and 6 the wall or support therefor.

My invention comprises a door latch, which is designated as a whole by the reference letter A, and a wall catch which is designated as a whole by the reference letter B. The latch includes a bore 7 which extends inwardly from the outer edge of the door, and communicating with the inner end of this bore is a transverse opening 8 in which a spindle 9 is axially mounted for rotation, one end of the spindle carrying a knob 10 and the other end being formed with an eye 11, said eye being disposed in the same plane as the spindle and projecting forwardly therefrom. Located in the outer end of the bore 7 is a tubular casing 12, the outer end of said casing terminating in an attaching flange 13, which is secured to the outer edge of the door 5 by any suitable means. The inner end of the casing is formed with an inwardly extending flange 14 constituting a stop and forming a resultant opening 15. Slidably mounted within the casing is a latch bolt 16, the inner end thereof being reduced to form an inwardly extending shank 17, said shank projecting through an opening 15. A guide 18 is fixed to the door 5 and receives the inner end of the shank 17. Disposed around the shank 17 and guide 18 is a U-shaped frame 19 which includes spaced legs 20—20 and a connecting portion 21, the ends of the legs being fixedly connected to the latch bolt 16 by any suitable means. Disposed around the shank 17 is a coil spring 22, one end thereof bearing against the latch bolt 16 and the other end bearing against the guide 18, said spring causing said latch bolt to be yield-

ably held in its projected position. Attached to the connecting portion 21 and extending inwardly therefrom toward the spindle 9 is an eye-bolt 23, which is connected to one end of a short chain 24, the other end of the chain being suitably connected to the spindle 9. It will thus be observed that upon rotation of the spindle, the chain 24 will be partially wrapped there-
5 around and at the same time the latch bolt 16, through the medium of the frame 19, will be drawn inwardly against the tension of the spring 22 until said latch bolt contracts with the flange or stop 14. Immediately upon release of the spindle 9, the
10 spring 22 will return the latch bolt 16 to its normal or operative position.
15

Secured to the wall or support 6 in a position to be engaged by the eye 11 of the spindle 9, is my improved wall catch B. This catch includes an attaching plate 25 which is secured to said wall by any suitable means. This plate is centrally formed with spaced upper and lower guides 26 and 27 which are rectangular in cross section.
20 Slidably mounted in the guide is a gravity catch, which is designated as a whole by the reference numeral 28. This catch includes a base 29 which is slidably mounted within the upper and lower guides 27 and which is formed with opposed stops 30—30 which coact with the lower guide 27 to retain said base against further downward movement. Centrally carried by the base 29 is a forwardly extending U-shaped bracket 31 which includes spaced legs 32—32, a connecting portion 33 and spaced clips 34—34 extending rearwardly from the connecting portion and secured to the base 29. A supporting
25 rod 35 is carried by the legs 32 of the bracket, and is disposed in spaced relation to the connecting portion 33 thereof. Slidably mounted on the rod 35 is a hook 36 having a rectangular base 37 which has slidable engagement with the connecting portion 33 of the bracket, and serves to prevent the rotation of said hook on the rod. The forward end of the hook is formed with a cam 38, and disposed around the rod 35 on either
30 side of said hook is a coil spring 39. One end of each spring bears against the hook and the other end against a respective leg 32 of the bracket. It will thus be observed that by means of these springs the hook is yield-
35 ably held on the rod against sliding movement.

In operation, after the door has been unlatched as above described and swung to its open position, the eye 11 of the spindle 9 will engage the cam 38 of the hook 36, and as a result, elevate the catch 28 to the position shown in Fig. 3 of the drawings. Upon further movement of the door toward the holder B, the catch will automatically drop
60 and assume the position as shown in Fig. 4

of the drawings. In this position the hook 36 will engage the eye 11, and thereby retain the door in its open position. When it is desired to disengage the holder, the spindle 9 is axially rotated by means of the knob 10,
70 and as a result, the eye 11 of said spindle will engage the hook 36 and cause said hook to slide longitudinally along the supporting rod 35 against the tension of the springs 39. This movement of the spindle is continued
75 until the eye 11 is disengaged from the hook. The door can then be readily closed and the hook will return to its normal position by means of the spring 39.

What is claimed is:

1. The combination of a latch including an axially rotatable spindle adapted to be secured to a door, a member carried by the spindle and a holder including a gravity hook adapted to be secured to a wall and automatically engage with the member carried by the spindle when the door is opened, said latch being yieldably supported for lateral movements and adapted to be disengaged from the spindle carried member upon rotation in one direction of the spindle.

2. The combination of a latch including an axially rotatable spindle adapted to be secured to a door, an eye formed on one end of the spindle, and a catch including a gravity hook adapted to be secured to a wall to automatically engage with the eye when the door is open, said hook being yieldably supported for lateral movements and adapted to be disengaged from the eye upon rotation in one direction of said spindle.

3. In a door wall catch, the combination of an attaching plate, and a gravity latch supported thereon for vertical and transverse movements.

4. In a door wall catch, the combination of an attaching plate, a gravity latch supported thereon for vertical and transverse movements, and means for yieldably retaining the latch against lateral movements.

5. In a door wall catch, the combination of an attaching plate, spaced upper and lower guides carried thereby, a base mounted in said guides for a limited sliding movement, a latch carried by the base for lateral movements, and yieldable means for retaining said latch in its normal position.

6. In a door wall catch, the combination of an attaching plate, spaced upper and lower guides carried thereby, a base mounted in said guides for a limited sliding movement, a bracket carried by the base, a rod supported by the bracket, a latch slidably on the rod, and means for yieldably holding the latch in its normal position.

7. In a door wall catch, the combination of an attaching plate, spaced upper and lower guides carried thereby, a base mounted in said guides for a limited sliding movement, a forwardly extending U-shaped

bracket carried by the base, a rod supported at its ends by the legs of the bracket, a latch 5
slidable on the rod, and coil springs respectively disposed around the rod intermediate the latch and the legs of the bracket for yieldably holding said latch in its normal position.

In testimony whereof, I affix my signature, in presence of two witnesses.

WILLIAM LANGE.
